(57) **CLAIM**

The ornamental design for a hat with adjustable shading, as shown and described.

DESCRIPTION

FIG. 1 is a perspective view of a hat with adjustable shading.

FIG. 2 is a front plan view of the hat of FIG. 1.

FIG. 3 is a back plan view of the hat of FIG. 1.

FIG. 4 is a right side plan view of the hat of FIG. 1.

FIG. 5 is a left side plan view of the hat of FIG. 1.

FIG. 6 is a top plan view of the hat of FIG. 1; and,

FIG. 7 is a bottom plan view of the hat of FIG. 1.

It should be noted that the broken lines shown are stitching but do not form part of the claimed design.

1 Claim, 4 Drawing Sheets
